UNITED STATES PATENT OFFICE.

CHARLES BELL, OF PHILADELPHIA, PENNSYLVANIA.

DESIGN FOR A LAMP.

Application filed March 27, 1925. Serial No. 12,917. Term of patent 3½ years.

To all whom it may concern:

Be it known that I, CHARLES BELL, a citizen of the United States, residing at Philadelphia, in the county of Philadelphia and State of Pennsylvania, have invented a new, original, and ornamental Design for Lamps, of which the following is a specification, reference being had to the accompanying drawing, forming part thereof.

The figure is a perspective view of a lamp, showing my new design.

I claim:

The ornamental design for a lamp as shown.

CHARLES BELL.
